UNITED STATES PATENT OFFICE

108,634

DESIGN FOR A CHEST OF DRAWERS

Della Halbert Whitehead, Del Rio, Tex.

Application December 30, 1937, Serial No. 73,983

Term of patent 14 years

To all whom it may concern:

Be it known that Della Halbert Whitehead, a citizen of the United States, residing at Del Rio, in the county of Val Verde and State of Texas, has invented a new, original, and ornamental Design for a Chest of Drawers, of which the following is a specification, reference being had to the accompanying drawing forming part thereof.

In the drawing the sole figure is a perspective view of a chest of drawers, showing my design, I claim:

The ornamental design for a chest of drawers as shown.

DELLA HALBERT WHITEHEAD.
